COMBINED THERMOSTATIC CONTROL AND ROCKER BUTTON ACTUATOR FOR AN ELECTRIC SWITCH

Harry W. Brown, Mukwonago, Wis., assignor to Cutler-
Hammer, Inc., Milwaukee, Wis., a corporation of Del-
aware

Filed Aug. 25, 1958, Ser. No. 52,375

Term of patent 14 years

(Cl. D26—13)

Fig. 6

Fig. 8

Fig. 7

Fig. 9

Figure 1 is an isometric view of a combined thermostatic control and rocker button actuator for an electric switch showing my new design;

Fig. 2 is a front elevational view;

Fig. 3 is a side elevational view of the left-hand end;

Fig. 4 is a side elevational view of the right-hand end thereof;

Fig. 5 is a top plan view thereof;

Fig. 6 is an isometric view of the combined thermostatic control and rocker button actuator for an electric switch in an operating position;

Fig. 7 is a front elevation view;

Fig. 8 is a side elevation view of the right-hand end; and

Fig. 9 is a top plan view thereof.

The dominant features of my design reside in the control button actuator portions shown in solid black lines in the drawing.

The legends and switch plate portions shown in dotted lines are for illustrative purposes only.

I claim:

The ornamental design for a combined thermostatic control and rocker button actuator for an electric switch, substantially as shown and described.
